UNITED STATES PATENT OFFICE

CARTER R. MASSIE, OF IRONTON, OHIO

COIN CONTROLLED GASOLINE VENDING MACHINE

Application filed March 14, 1930. Serial No. 435,853.

This invention relates to new and useful improvements in coin controlled gasoline vending machines and has for one of its objects to provide, in a manner as hereinafter set forth, a gasoline vending machine of this character which embodies means whereby to enable a purchaser to wait on himself, thus eliminating the necessity of an attendant to dispense the gasoline.

10 Another important object of the invention is to provide a coin controlled gasoline vending machine of the character set forth adapted to dispense a predetermined quantity of gasoline upon the insertion of a coin therein.

15 to and the invention aims further to provide a novel construction and arrangement of parts whereby a plurality of coins may be successively inserted in the machine in order that the desired quantity of gasoline may be had, a predetermined quantity of gasoline being dispensed after the insertion of each coin.

Another important object of the invention is to provide a gasoline vending machine of the character set forth embodying means whereby a quantity of gasoline may be regulated in a manner to compensate for fluctuation which may occur in the sale price of same.

30 Other objects of the invention are to provide a coin controlled gasoline vending machine of the character described which will be simple in construction, strong, durable, efficient in its use and which may be manufactured and installed at low cost.

All of the foregoing and still further objects and advantages of the invention may become apparent from a study of the following specification, taken in connection with the accompanying drawings wherein like characters of reference designate corresponding parts throughout the several views, and wherein:

45 Figure 1 is a view in side elevation of a gasoline dispensing machine constructed in accordance with this invention.

Figure 2 is a fragmentary view in front elevation showing the lower portion of the

50 housing.

Figure 3 is a vertical sectional view of the invention.

Figure 4 is a detail view in section showing the means for regulating the quantity of gasoline to be dispensed after the insertion 55 of each coin.

Figure 5 is a view taken substantially at right angles to Figure 4 looking from right to left of said Figure 4.

Figure 6 is a fragmentary view in horizontal section taken substantially on the line 6—6 of Figure 5 looking downwardly as indicated by the arrows.

Figure 7 is an enlarged detail view in horizontal section showing the coin controlled 65 mechanism of the machine and taken substantially on the line 7—7 of Figure 5.

Figure 8 is a detail view in vertical section taken substantially on the line 8—8 of Figure 7 looking in the direction indicated by 70 the arrows.

Figure 9 is a vertical sectional view taken substantially on the line 9—9 of Figure 7 looking in the direction indicated by the arrows.

Figure 10 is an enlarged detail view in vertical section showing one of the adjustable stop devices which regulates the quantity of gasoline which will be dispensed with the insertion of a single coin.

Figure 11 is a view in horizontal section taken substantially on the line 11—11 of Figure 10 looking downwardly in the direction indicated by the arrows.

Figure 12 is a detail view in bottom plan 85 of the element illustrated in Figure 10.

Figure 13 is a detail view in end elevation of the device illustrated in Figure 10.

Figure 14 is a fragmentary perspective view showing the portion of the coin controlled vertically shiftable tube through 90 which the coin is inserted.

Figure 15 is a detail view in perspective showing the spring controlled vertically slidable coin actuated keeper bar which limits 95 the downward sliding movement of the vertically reciprocable tube.

Figure 16 is a detail view in perspective showing the slidable coin actuating device.

Figure 17 is a detail view in perspective 100

showing the vertically reciprocable discharge pipe which is mounted in the gasoline measuring tank.

Figure 18 is a fragmentary view in elevation showing the upper end portion of the slotted threaded bar upon which the stop members are adjustably mounted.

Referring to the drawings in detail and to Figures 1, 2 and 3, thereof in particular, it will be seen that the reference numeral 1 designates a vertically disposed cylindrical metallic casing mounted on the integral bottom wall 2 which, in conjunction with the flange 3 constitutes a supporting base for the casing. The upper end of the casing is closed by an integral top wall 4 and said casing is further provided on one side with an opening which is closed by a swingable door 5, said opening for the purpose of permitting access to be had to the interior of the casing. The upper wall 4 of the casing constitutes the bottom of a transparent cylindrical tank 6 having a closure plate 7 on its upper end. Surrounding the glass cylinder 6 and spaced therefrom is the usual guard 8. A pump 9 of conventional construction and driven by an electric motor 10 is interposed in a supply pipe 11 from a suitable source of supply and which extends upwardly through the casing 1 and is provided with a branch pipe 12 which projects upwardly into the tank 6 to a point adjacent the closure plate 7 for discharging gasoline into said tank when the pump 9 is actuated. The upper end of the pipe 11 extends through the wall 4 of the tank and is provided with a manually operable valve 13 by means of which the tank 6 may be drained when it is so desired. As clearly seen in Figure 3 of the drawings, the pump 9 is mounted on the bottom wall 2 of the casing 1.

An elongated housing 14 is mounted on the wall 4 and depends therefrom in the casing 1 and said housing forms a gasoline receiving chamber 15. A stand pipe 16 communicates with the lower end of the chamber 15 and said pipe has its free end portion extending outwardly through the casing 1 adjacent the upper end thereof and then turned downwardly and has a hose 17 connected to the free end thereof. A manually operable control valve 18 is mounted in the free end portion of the discharge pipe 16 to control the passage of gasoline therethrough. A vertically disposed guide tube 19 extends upwardly from the bottom wall 2 of the casing 1 in vertical alignment with the chamber 15 in the housing 14. The guide tube 19 is a part of the vertical casting 20 mounted in the casing 1. The bore of the member 19 is polygonal and has mounted for vertical sliding movement therein the polygonal tube 21 which extends slidably through the lower end of the housing 14 and longitudinally through the chamber 15 formed by said hous-

ing. The upper end of the tubular member 21 terminates in a solid threaded portion 24 upon which is mounted a tubular pipe section 25 which extends slidably through the wall 4 and into the tank 6. The lower end portion of the pipe section 25 is provided with discharge ports 26 whereby gasoline which enters said pipe section from the tank 6 is discharged into the chamber 15. As best seen in Figure 14 of the drawings, the vertically adjustable polygonal tube 21 has one side provided with a longitudinally extending channel 27. A horizontally disposed block 28 is fixed in the tubular member 21 and provided with a transverse slot 29 which, as best seen in Figure 8 of the drawings, has one side in registry with the slot 30 in the wall of said member 21. Above the slot 30 and closely adjacent thereto, the wall of the tubular member 21 is laterally offset to provide an abutment 31. The casting 20 is further provided with a polygonal chamber 32 in which is mounted a threaded tubular bar 33 having longitudinally extending slots in diametrically opposite sides thereof. A plurality of internally threaded collars 34 are mounted for vertical adjustment on the member 33 and fixed on each of said collars is a block 35 which encircles the member 33 for sliding movement thereon and is provided with openings 36 and 37 which are in registry with the slot in the member 33. The blocks 35 are secured against rotation on the collars 34 through medium of the fastening screws 38. The chamber 32 communicates throughout its length with the chamber in which the vertically shiftable member 21 is mounted through the passage 39.

Opposite the passage 39 the chamber 32 is provided with a longitudinally extending passage 40 through which extends from the block 35 the arms 41 having the connecting portion 42 between their outer ends through which is threaded a sleeve 43 having a polygonal tool receiving head 44 thereon.

Mounted for sliding movement through the polygonal openings 36 and 37 of each of the blocks 35 is a polygonal stop member 45 which has one end portion projecting through the passage 39 into the channel 27 of the vertically shiftable member 21 for engagement with the abutment 31 of said member 21, as clearly illustrated in Figure 8 of the drawings. The free end of the member 45 has journaled therein a roller 46 adapted to bridge the slot 30 of the member 21. The stop member 45 has an integral circular portion 47 which projects outwardly from the opposite side of the block 35 between the arms 41 and extending slidably through the sleeve 43. A flange 48 is mounted on the inner end of the circular portion 47 for abutting engagement with the adjacent side of the block 35 and a coil spring 49 encircles said circular portion 47 and has one end impinged against

the sleeve 43 and the opposite end impinged against the flange 48 for yieldingly urging the inner end of the polygonal stop member 45 into engagement with the polygonal member 21. A cross pin 50 extends transversely through the circular portion 47 adjacent to and spaced from the inner end of the sleeve 43 for engagement by said sleeve when the same is threaded inwardly to positively lock the stop member 45 against horizontal sliding movement through the blocks 35. A pointer 51 is mounted on one of the arms 41 and extends outwardly therefrom adjacent one side of the casting 20 to co-act with the indicating mark 52 (see Figure 5) in order to facilitate the adjustment of the blocks 35 and the stop members 45 on the threaded rod 33. This adjustment is accomplished by removing the pin 38 and threading the collars 34 up or down on the tubular threaded rod 33 until the stop members are disposed at the desired point thereon. This is for the purpose of varying the quantity of gasoline which will be dispensed as the price of the gasoline varies.

The casting 20 is further provided with a vertical coin receiving chamber 53 which communicates throughout its length with the polygonal chamber in which the vertically adjustable polygonal tubular member 21 is mounted. A slotted coin chute 54 is rigidly mounted on an intermediate portion of the member 21 and extends outwardly therefrom through a passage 55 in the casting 20 and the slot 56 in the casing 1. The coin chute 54 is secured to the member 21 by any suitable means such as welding. As best seen in Figure 9 of the drawings, the same is provided with a horizontally disposed transversely extending passage 57 which is open on both sides and which communicates with the slot 29 in the block 28 through a slot 58 in the adjacent wall of the member 21. The opposite side walls of the passage 57 are provided with the complementary grooves or channels 59 in which is slidably mounted a plunger rod 60 which is slidable through the outer end of the coin chute 54 and has fixed on its outer end an actuating knob 61 and on its inner end a flat horizontally disposed head 62 adapted for sliding movement through the passage 57 and into the passage 55 formed in the casting 20.

Mounted on the vertically shiftable polygonal tube member 21 below the coin chute 54 is an actuating handle 63 which also extends outwardly through the passage 55 in the casting 20 and the slot 56 in the casing 1. Suitable contacts 64 and 65 are mounted on the vertically shiftable member 21 and the casting 20, respectively, for engagement with each other when said member 21 is raised to the limit of its outward stroke for the purpose of energizing the electric motor 10 through the conductor wires 66. The con-

ductor wires lead from any suitable source of current supply.

In use, the purchaser grasps the handle 63 and elevates the polygonal member 21 in a manner to raise the pipe section 25 in the tank 6 and engage the contact 64 with the contact 65 to energize the motor 10. In this position the abutment 31 on the member 21 is disposed slightly above the uppermost of the stop bars 45 and thus when the tank 6 is filled the circuit to the motor 10 may be broken by lowering the member 21 into engagement on the uppermost stop member 45. A coin is then inserted in the passage 57 and the plunger rod 60 is actuated in a manner to slide the coin inwardly through the slot 58 of the wall of the member 21 and through the slot 29 in the block 28. As the coin passes through the slot 29, one end will project through the slot 30 and engage with the roller 46 on the end of the stop bar 45 and slide said bar outwardly against the tension of the coil spring 49 and disengage the stop bar from the abutment 31. The member 21 may then be lowered until the abutment 31 engages the subjacent stop member 45. This lowering of the member 21 lowers the pipe section 25 in the tank 6 and all of the gasoline which is disposed above the pipe section after the same has been lowered will flow therethrough into the chamber 15 through the portion 26. From the chamber 15 gasoline is conveyed through the stand pipe 16 and the hose 17 to the tank of the vehicle or to any other receptacle to be filled. The chamber 15 is at all times filled to the level of the uppermost portion of the stand pipe 16. When more gasoline is desired, another coin is then inserted in the chute 54 and the operation is repeated until the member 21 has reached its lowermost point after which the same is again raised to its uppermost point to close the circuit to the motor 10 and refill the tank 6. When the coin passes the rollers 46 of the stop member 45 the same may be projected through the slot provided therefor and designated by the reference numeral 67 in the rear wall of the member 21, said coin dropping into the chamber 53 where the same may gravitate into a suitable receptacle A as seen in Figure 3.

It is believed that the many advantages of a coin controlled gasoline vending machine constructed in accordance with this invention will be readily understood, and although the preferred embodiment of the invention is as illustrated and described, it is to be understood that changes in the details of construction may be had which will fall within the scope of the invention as claimed.

What is claimed is:

1. A coin controlled gasoline vending machine of the character described comprising a casing, a tank mounted thereon, means for discharging gasoline into the tank, a vertically shiftable member disposed in the cas-

ing, a discharge pipe mounted on the upper end of the member and extending for vertical sliding movement into the tank, an abutment on the vertically shiftable member, a threaded tubular rod mounted in the casing in spaced parallel relation to the vertical member, a series of stop bars adjustably mounted in longitudinally spaced relation on the threaded bar and engageable with the member in a manner to retain the same against downward movement and coin controlled manually operable means for disengaging said stop bars from said member.

2. A coin controlled gasoline vending machine of the character described comprising a casing, a tank mounted thereon, means for discharging gasoline into the tank, a vertically shiftable member mounted in the casing, a discharge pipe mounted on the upper end of the member and extending for vertical sliding movement into the tank, a discharge hose having communication with the pipe, a threaded rod mounted in the casing in spaced parallelism to the vertically shiftable member, and a series of vertically spaced, spring controlled stop members mounted for horizontal sliding movement on the threaded rod in yielding engagement with the vertically shiftable member in a manner to retain the same against downward movement and coin controlled manually operable means for disengaging said stop bars from the member to permit downward movement thereof.

3. A coin controlled gasoline vending machine of the character described comprising a cylindrical casing, a tank mounted thereon, means for discharging gasoline into the tank, a gasoline receiving chamber disposed in the casing, a vertically shiftable member mounted for sliding movement in the casing and extending upwardly through the chamber, a pipe rigidly mounted on the upper end of the member and extending for vertical sliding movement into the tank, said pipe having communication with the tank and the chamber in a manner to convey the gasoline from said tank into said chamber, a discharge hose having communication with the chamber, a vertically disposed threaded rod mounted in the casing in spaced parallelism with the vertically shiftable member, a series of vertically spaced spring controlled stop bars mounted for horizontal sliding movement on the threaded rod, means for adjusting the stop bars vertically on the threaded rod, an abutment on the vertically slideable member for engagement with the stop bars in a manner to retain said member against downward movement and coin controlled manually operable means for disengaging the stop bars from the abutments in a manner to permit downward movement of the member.

In testimony whereof I affix my signature.
CARTER R. MASSIE.
